Attorney

UNITED STATES PATENT OFFICE.

JOSEPH GEORGE MEDLENKA, OF CROWLEY, LOUISIANA.

TROUSERS HANGER.

Application filed October 2, 1928. Serial No. 209,756.

This invention relates broadly to that class of inventions known as garment hangers, and has more particular reference to the species employed especially as a hanger for men's trousers.

The purpose of the invention is to provide a simple, inexpensive, and efficient means which is susceptible of easy application to one or more pairs of trousers, and which is constructed with a view toward promoting compactness and convenience of arrangement of the parts and to make the invention suitable for fulfilling the requirements of a device of this class.

15 The particular structural details and their specific association, will become more readily apparent from the following description and drawings.

In the drawings:—

20 Figure 1 is an elevational view of the trousers hanger showing the manner in which it is applied.

Fig. 2 is an end view of the same on an enlarged scale.

25 Fig. 3 is a sectional view taken approximately upon the plane of the line 3—3 of Fig. 1, the trousers being removed.

Fig. 4 is a perspective view of an end portion of one of the principle parts of the structure.

30 In carrying out the invention, I provide a pair of clamping and pressure producing plates 5. These are preferably constructed of light weight metal. Each plate has its lower edge bent as at 6, to form a reinforcing rib, and has its upper edge bent into a hook as at 7. The ends of the plates are formed with projections 8 of the type represented clearly in Fig. 4.

40 It follows that these two plates are disposed in side by side clamping relation against the trousers somewhat as indicated in Fig. 2, whereupon flexible strips of rubber 9 are brought into play. These strips of rubber are formed with longitudinally spaced holes which snap over the projection heads 8.

45 Cooperable with the hooked edges 7 are flexible suspension elements. These are of segmental configuration, each being designated by the reference character 10 and having its lower edge clamped firmly beneath the

hook, by clenching the hook against it, as shown in Fig. 2. These segmental cross pieces extend above the cuffs 11 of the trousers 12, where they are provided in their crown portions with openings disposed in registry with each other to receive the eye portion of a suspension hook 13.

55 It is believed that the device is an advantageous contribution to the art, first, because it can be easily adjusted to the trousers, and secondly because it will hold several pairs of trousers, and keep the cuffed ends in better shape.

60 In most of the trousers hangers, the cuffs droop over the hanger and get badly out of shape. The segmental cross sections hold the cuffs together. The hanger is dependable and positive in action, and holds the trousers tight and it is simple and inexpensive as well as exceptionally small in construction, so that it can be conveniently stored in a hand grip, or traveling bag.

65 These and other features and advantages of the invention have doubtless been made apparent from the description and drawings. Consequently, a more lengthy description is regarded unnecessary.

70 Minor changes in shape, size, and rearrangement of details coming within the field of invention claimed, may be resorted to in actual practice if desired.

75 Having thus described my invention, what I claim as new is:—

80 As a new article of manufacture, a trousers hanger of the class described comprising a pair of duplicate flat clamping plates, formed on their lower edges with bent flanges providing reinforcing beads, and provided at their opposite ends with headed projections, the upper edges of said plates formed into hooks, a pair of segmental cross members, having their lower edge portions clamped beneath said hooks, said cross members being formed with registering openings, and a suspension hook engaged in said openings, together with flexible end strips having apertures for selective reception of the headed projections on the ends of said plates.

85 90 95 95 In testimony whereof I affix my signature.

JOSEPH GEORGE MEDLENKA.
